ATTORNEY

UNITED STATES PATENT OFFICE.

EDWIN E. KEOUGH, OF SAN FRANCISCO, CALIFORNIA, ASSIGNOR OF ONE-HALF TO
H. M. GOLDBERG, OF SAN FRANCISCO, CALIFORNIA.

AUTOMOBILE-RADIATOR-CAP LOCK.

1,387,819.

Specification of Letters Patent. Patented Feb. 8, 1921.

Application filed November 11, 1919. Serial No. 387,185

To all whom it may concern:

Be it known that I, EDWIN E. KEOUGH, citizen of the United States, residing at San Francisco, in the county of San Francisco, State of California, have invented a new and useful Automobile-Radiator-Cap Lock, of which the following is a specification in such full and clear terms as will enable those skilled in the art to construct and use the same.

My invention relates to locks for automobile radiator caps, and its object is to prevent the theft of the cap when it has a valuable temperature indicator, or an ornamental figure or design attached to it.

Another object of the invention is to provide for attaching and detaching the locking means quickly.

Other objects of the invention will appear as the description proceeds.

An embodiment of the invention is shown in the accompanying drawings in which the same reference numeral is applied to the same portion throughout, but I am aware that there may be modifications thereof.

Figure 1 is a view of an automobile radiator cap with a temperature indicator attached thereto showing the locking means, partly in section.

Fig. 2 is a plan of the clamp and lock.

The numeral 1 indicates the top of a radiator on an automobile or truck, 2 the water filler pipe, and 3 the cap which is generally made with the external threads 4

that engage the internal threads of the filler 35 pipe.

A temperature indicator of a well known construction is securely fastened to the cap. Other devices are often attached to a radiator cap, some of which are merely ornamental, but all are more or less valuable.

To prevent the theft of the cap with its ornament, a form of clamp shown in Fig. 2 is provided consisting of a one piece loop made preferably of sheet steel 11, and it 45 has the pin 9 riveted in as shown. The projecting portions 12 and 12' could be held by a padlock as in Fig. 1, but in this instance a threaded bolt 13 is used to draw the clamp together, thread being cut in the hole in 50 projection 12'. A hole 14 is provided in the bolt for the padlock 7'.

What I claim is as follows, but various modifications may be made in the construction shown in the drawings and above particularly described form, within the purview of my invention:

A locking device for motormeters comprising a spring member adapted to surround a radiator filling neck, means to lock 60 the two ends of the locking device together, and a lug projecting inwardly from said device to engage the filling cap and prevent it from being turned.

In testimony whereof I have hereunto set 65 my hand this 1st day of November, A. D. 1919.

EDWIN E. KEOUGH.
